TEMPERATURE CONTROL FOR PAPER MILLS
AND THE LIKE

Hazor J. Smith, Longmeadow, Mass., assignor, by
means assignments, to General Motors Corpora-
tion, Detroit, Mich., a corporation of Dela-
ware

Application June 24, 1935, Serial No. 38,056

14 Claims.

(CL. 34—43)

This invention relates to temperature-control systems, and more particularly to a system for controlling the temperature of the drying rolls in paper mills and the like.

An object of the invention is to provide an automatic control for the moisture content of the sheet which is discharged from the drying rolls of a paper mill.

Another object is to provide an accurate and automatic system, controlled by variations in the moisture content of the sheet which is received by the drying rolls, for varying the temperature of the rolls so as to discharge the sheet with a uniform moisture content.

Another object is to provide a system of the above type which may be readily adjusted to accommodate different types of sheet, or stock having different moisture contents.

Another object is to provide a system of the above type which is adapted to operate in conjunction with present equipment, whereby the cost of installation is reduced to a minimum.

Another object is to provide a system for maintaining the rolls at a predetermined temperature during periods when no sheet is being received thereby.

Another object is to provide a simple, convenient and dependable device of the type above indicated.

Other objects will be apparent from the following description.

The invention is primarily intended for use in connection with the drying rolls of a paper mill. In such mills the sheet is passed successively over a plurality of rolls which are maintained at suitable temperatures by heating means, such as steam, and are adapted to discharge the sheet with a predetermined moisture content. A feature of the present invention consists in utilizing the variations of moisture content of the incoming sheet to control the steam supplied to the rolls in such manner as to compensate for said variations.

In one embodiment, the tension of the incoming sheet is used as a measure of the moisture content. A tensioning roll, such, for example, as a Stickles roll, is held against the incoming sheet in such manner that the position of the roll is determined by the moisture content of the sheet at any instant. Inasmuch as the tensioning roll is responsive to minor changes in moisture content, means is provided to integrate the movement of the roll so as to effect a control only in accordance with the average moisture content of the sheet over predetermined intervals.

In accordance with the present invention, the position of the tensioning roll is translated into movement of a steam supply valve by means of a reversible motor-control unit. In order to provide means for adjusting the range of control of the motor-control unit in accordance with changes in stock, a second motor-control unit is provided which is operated by a hand control or by an automatic thermostat. The ratio of control effected by the first and second motor-control units may be varied in order to provide the desired result. The automatic thermostat may be controlled in accordance with the steam condensate temperature at a selected roll, for the purpose of maintaining the temperature of the rolls substantially uniform when the control of the first unit is interrupted, as, for example, in response to a break in the sheet. Means is provided for manually connecting either the hand control or the thermostat into the circuit, as desired.

Other features of the invention consist in the various details of construction and combination of parts as hereinafter more fully set forth.

The broader aspects of the invention will be better understood by referring to the following description, taken in connection with the accompanying drawings in which a preferred embodiment has been disclosed for purposes of illustration only.

In the drawings,

Figure 1 is a diagrammatic view of a temperature-control system embodying the present invention;

Figure 2 is a front elevation of the automatic control switch;

Figure 3 is a side view thereof;

Figure 4 is a detail view of the automatic control mechanism;

Figure 5 is a front elevation of the control panel;

Figure 6 is a wiring diagram showing the connections of the signal lights;

Figure 7 is a section of the indicating unit, taken along the line 7—7 of Figure 8;

Figure 8 is a side view of the indicating unit; and

Figure 9 is a wiring diagram showing the connections between the hand control, automatic temperature control and motor-control unit.

In the following description and in the claims, certain specific terms have been used for convenience in referring to the various details of the invention. These terms, however, are to be interpreted as broadly as the art will permit.

Referring to the drawings more in detail, the invention is shown in Figure 1 as applied to the drier of a paper mill which comprises a plurality of rolls 10 over which a sheet 11 of paper is passed in the usual manner for successively drying the same as it passes over the rolls. The rolls may be heated by steam supplied from a header 12 and fed to the individual rolls 10 by communicating pipes 13. The condensate from each roll is collected in a well 14 and is removed through a pipe 15 which connects with a drain line 16. Steam may be supplied to the header 12 from a main 17 having a control valve 20 which may be operated by a lever 21 in accordance with the automatic control mechanism to be described.

The lever 21 is controlled by a pair of motor-control units 25 and 26 having arms 27 and 28 respectively which are connected by links 29 and 30 to a control lever 31. The control lever 31 is connected to the lever 21 by means of a link 32, the point of connection of the link 32 to the control lever 31 being varied by a slider 33 having a hand set screw 34. By varying the position of the slider 33, the ratio of the control of the motor-control units 25 and 26 may be adjusted. When one of the control units is stationary, the link 29 or 30 which is connected thereto serves as a fulcrum about which the control lever 31 may pivot in response to movement of the other motor-control unit. In the form disclosed, the motor-control unit 26 operates as a master control for varying the operating range of the valve 20, whereas the motor-control unit 25 operates as an automatic control which is actuated in accordance with the moisture content of the incoming sheet.

The control device for actuating the motor-control unit 25 is shown more in detail in Figure 4. It comprises a tensioning roll 38 which is mounted upon an arm 39, pivoted as at 40, and held by a weight 41 against the sheet 11 of paper which is being supplied to the drying rolls. The arm 39 is connected to a valve 42 which controls the flow of fluid, such as water, through a pipe 43 leading to a cylinder 44. The cylinder 44 is provided with a discharge line 45 regulated by a valve 46. The cylinder 44 carries a piston 47, the position of which is determined by the quantity of fluid within the cylinder.

The piston 47 carries a piston rod 48 which is connected to a belt 49 passing over pulleys 50 and 51 and having stops 52 and 53 adapted to engage the lever 21 for controlling the position of said lever in accordance with the movement of the belt 49. The spacing between the stops 52 and 53 permits a certain amount of movement of the belt 49 without actuating the lever 21. Suitable weights 54 and 55 may be associated with the belt 49 for maintaining the same in operating condition and to determine the operating characteristics of the device.

A belt 59 may also be connected to the piston rod 48, as by an arm 60. Said belt 59 may be passed around a pulley 61 and thence over a pulley 62 of a control switch 63 which is adapted, by its position, to determine the operating position of the motor-control unit 25. A weight 64 may be hung on the end of the belt 59 to hold the same in frictional engagement with the pulley 62.

The control switch 63 is shown more in detail in Figures 2 and 3 as comprising the pulley 62, over which the belt 59 passes, and a pair of contacts 68 mounted upon a shaft 69 which carries

the pulley 62 and turns therewith. The contacts 68 are adapted to alternately engage contacts 71 carried by a contact arm 72 which is supported by a sleeve 73 journalled on the shaft 69. The contact arm 72 carries a pair of brushes 70 which are electrically connected, respectively, to the contacts 71 and are adapted to engage sets of stationary contacts 74 and 75 which are mounted on a stationary support 76.

The construction is such that rotation of the pulley 62 in one direction closes one pair of contacts 68 and 71 and transmits a force therethrough to cause rotation of the contact arm 72. Rotation of the pulley 62 in the opposite direction breaks the first-mentioned pair of contacts 68 and 71, closes the other pair of contacts 68 and 71, and causes rotation of the contact arm 72 in the opposite direction. The contacts 68 and 71 thus constitute reversing contacts to complete a circuit to one or the other of the brushes 70, depending upon the direction of rotation of the pulley 62. The position of the brushes 70 determines the position of the motor-control unit 25 by a circuit, to be described.

For limiting the movement of the pulley 62, a stop 77 is provided which is adapted to engage the belt 59 when the pulley 62 is moved to either extreme position. A contact 78 may be carried by the stop 77 to engage one of a pair of contacts 79 for closing the circuit to the signal 30 lights, to be described.

The various contacts 74 and 75 are connected by a cable 80 (Figure 1) to the motor-control unit 25 in such manner that the arm 27 of the motor-control unit is caused to take up a position corresponding to the position of the brushes 70 on said contacts.

In the operation of the control device illustrated in Figure 4, the tensioning roll 38 presses against the sheet 11 and causes movement of the arm 39, dependent upon the moisture content of the sheet. In normal operation, the arm 39 is caused to oscillate in accordance with the instantaneous variations in the sheet. In so doing, it causes the valve 42 to operate in a corresponding manner. If the valve 42 admits water to the cylinder 44 at a rate equal to the rate of discharge of water through the discharge line 45, no movement of the piston 47 will take place. If the valve 42 admits water to the cylinder 44 at a rate in excess of or less than the rate of discharge through the discharge line 45, the water level will rise or fall, respectively, in the cylinder 44 and will cause corresponding movement of the piston 47, which is transmitted by the belt 59 to the control switch 63. The control switch 63 actuates the motor-control unit 25 to progressively open or close the valve 20.

The manner of connection is such that an increase in the moisture content of the sheet 11 causes the valve 20 to be opened so as to supply additional steam to the rolls 10, whereby the temperature of said rolls is raised an amount adapted to compensate for the extra moisture contained in the incoming sheet. If the moisture content of the incoming sheet decreases, a reverse operation takes place, the piston 47 being raised or lowered in accordance with the average opening of the valve 42 which, in turn, is determined by the average moisture content of the sheet 11 over a given interval.

The contacts 79 may be connected to heating coils 82 which are associated with thermostatic switches 83. Each switch 83 is adapted to close a contact 84 to a signal light 85 which may be

mounted, for example, on the control panel 86, as illustrated in Figure 5. The connection is such that, when one of the contacts 79 is closed a sufficient length of time to actuate the switch 83, the signal light 85 is lighted so as to indicate to the operator that an extreme change is taking place. The switch 83, however, is sufficiently slow-acting as to prevent the signal light 85 from being energized in response to momentary closing of the contacts 79. When the pulley 62 is moved to either of its extreme positions, the stop 77 engages the belt 59 to limit the movement of the pulley. If further movement of the piston 47 takes place, the belt 59 slips about the periphery of the pulley 62. The stop 77 also provides manual means for adjusting the pulley 62 with respect to the belt 59.

The second motor-control unit 26 may be connected to a hand switch 89 (Figure 1) or to an automatic thermostat 90, both of which may be mounted upon the control panel 86.

The hand switch 89 may be of the type described in my copending application Serial No. 657,237, filed February 17, 1933, for Control by integration. It may comprise, for example, a shaft 91 (Figures 7, 8 and 9) carrying an arm 92 having a pair of contacts 93 adapted to engage contacts 94 mounted on a contact arm 95. The contact arm 95 is mounted for rotation on a sleeve 96 which is journaled eccentrically about the shaft 91. A control handle 97 may be connected to the shaft 91. The contact arm 95 carries a pair of brushes 98, 99 which engage sets of contacts 100, 101 in accordance with the position of the control handle 97. The contacts 100, 101 are connected to the motor-control unit 26 in the manner to be described.

The thermostat 90 may be of the type shown in my Patent No. 1,952,571, dated March 27, 1934. It may comprise, for example, an arm 103 pivoted, as at 104, and actuated by an expansible bellows 105 in accordance with the temperature of the fluid therein. A spring 106 may be used to adjust the operating range of the thermostat. The arm 103 carries a pair of contacts 107 which are adapted to engage contacts 108 carried on a contact arm 109 which is pivoted, as at 110, to the arm 103. The contact arm 109 carries a pair of brushes 111 which are adapted to engage sets of contacts 112 and 113. The contacts 112 and 113 may be connected to the motor-control unit 26 in the manner to be described, whereby the motor-control unit may be operated in accordance with the position of the thermostat.

The bellows 105 may be connected by a flexible tube 114 to a bulb 115 which may be mounted in a suitable well in the return condensate line of one of the rolls 10. The thermostat accordingly is responsive to the temperature of the steam condensate in the selected roll 10 and is adapted to actuate the motor-control unit 26 so as to control the steam supplied to the roll in a manner adapted to maintain the roll at a predetermined temperature.

In order to indicate to the operator the position of the motor-control unit 26, an indicating unit 120 is provided (Figures 5, 7 and 8) having an indicator 121 moving over a scale 119, calibrated to show the angular position of the arms 28 of the motor-control unit 26. This indicating unit 120 may comprise a shaft 122 carrying the indicator 121. A commutator 123 and a worm gear 124 may also be connected to the shaft 122.

The worm gear 124 may be driven through a

gear train 125 from a pinion 126 carried by a reversible motor 127. A plurality of sets of stationary contacts 128, 129 and a contact 130 are mounted on a support 131 in position to engage the commutator 123 as the commutator is rotated by the motor 127.

The motor-control units 25 and 26 and the indicating unit 120 may be of similar construction with the exception of the indicator 121, which, in the case of the motor-control units 25 and 26, is replaced by the arms 27 and 28. The units may, for example, be of the type described in my copending application, above-mentioned. A suitable control circuit for the indicating unit 120 is illustrated, for example, in Figure 9. In this figure, the reversible motor 127 is shown as a reversible shaded pole motor having a field winding 132 which may constitute the secondary of the transformer 133, the primary 134 of which may be connected to a source of A. C. supply. The motor is provided with a pair of shading coils 135 which, when energized, are adapted to cause rotation of the motor in one direction, and another pair of shading coils 136 which are adapted to cause rotation of the motor in the opposite direction. These coils 135 and 136 may be connected to a double-pole, double-throw switch 137 having a set of poles 138 connected by leads 139 to the contacts 93 of the hand switch 89 and a set of poles 140 connected by leads 141 to the contacts 107 of the thermostat 90. The contacts 100 of the hand switch 89 and the contacts 112 of the thermostat 90 may be connected by cables 145 and 146, respectively, to a junction box 147 which is connected by a cable 148 to the contacts 128 of the indicator unit 120. The contacts 101 of the hand switch 89 and the contacts 113 of the thermostat 90 may be connected by cables 149 and 150, respectively, to a junction box 151 which is connected by a cable 152 to the contacts 129 of the indicator unit 120. The contact 130 of the indicator unit 120 is connected by a line 153 to the field winding 132 of the motor 127.

The above connections are such that when the switch 137 is in one position, the hand-control switch 89 is connected in the circuit. If then the handle 97 is turned in one direction, for example, in a counter-clockwise direction, as viewed in Figure 9, the pair of contacts 93 and 94 at the left is closed, thereby completing the circuit from the shading coils 135 through the switch 137 and one lead 139 to the selected contacts 93 and 94, thence to the brush 98, one of the contacts 100, through the cables 145 and 148 to one of the contacts 128, thence through the commutator 123, the contact 130 and the return line 153 to the field winding 132 of the motor 127. The motor is then caused to operate in a given direction until the circuit is broken by the commutator 123 leaving the contact 128 which is energized at that moment. If the handle 97 is moved in the opposite direction, the opposite pair of contacts 93, 94 is closed, thereby completing a circuit through the brush 99, a contact 101, cables 149, 152 to a contact 129 and energizing the opposite coils 136, which causes a reverse movement of the motor until the commutator 123 breaks contact with the contact 129 which is energized at that moment. The motor 127 is thus reversibly and progressively operated in accordance with the position of the handle 97. The contacts 128 and 129 may be relatively displaced to provide different positions of the motor-control unit in opening and closing the valve 20.

When the switch 137 is thrown into the oppo-

site position, the hand-control switch 89 is disconnected and the thermostat 90 is connected in the circuit. The control of the motor 127 by the thermostat 90 is then the same as that above 5 described in connection with the hand switch, the motor being reversibly and progressively actuated in response to temperature variations registered by the thermostat 90.

It is to be understood that the connections between the contacts 74 and 75 of the control switch 63, and the motor-control unit 25 are similar to those above described. This connection is illustrated in Figure 1 as comprising a cable 80 connecting the control device 63 with 10 the motor-control unit 25. It is also to be noted that the motor-control unit 26 and the indicating unit 120 are connected in parallel so that the indicator 121 shows at all times the position of the motor-control unit 26. The switch 137 15 is connected to a junction box 155 which is connected in parallel by cables 156 and 157, respectively, to the motor-control unit 26 and the indicating unit 120. The switch 137 may be operated by a handle 158 mounted upon the control panel 20 25 86. The control panel may also carry a suitable temperature recorder 159, a steam pressure recorder 160 and a chart 161.

In the operation of this system, the handle 158 is normally in a position such that the hand-control switch 89 is connected in circuit, whereby 30 the position of the motor-control unit 26 and the indicator unit 120 are governed by the position of the handle 97. Assuming a paper having predetermined characteristics to be passing over the 35 various rolls 10, the tensioning roll 38 will take up a position depending upon the moisture content of the paper, thereby causing the piston 47 and the belts 49 and 59 to take up corresponding positions. The motor-control unit 26 is then 40 actuated by manipulation of the handle 97 so as to bring the lever 21 into engagement with the stop 53 of the belt 49, whereby the control of the steam supply is taken by the belt 49. The stop 77 of the control switch 63 is then adjusted to 45 the central position by causing the pulley 62 to slip with respect to the belt 59. Thereafter, the steam supply will be under the control of the tensioning roll 38 and the motor-control unit 25. Said unit operates to produce minor variations 50 in the steam supply in accordance with the instantaneous positions of the control switch 63 caused by changes in the average moisture content of the sheet.

If the moisture content of the sheet changes 55 suddenly or becomes such that the control switch 63 is actuated to the limit of its movement, thereby closing one of the contacts 79, one of the indicating lights 85 on the panel 86 will be energized to indicate to the operator that a change 60 is taking place. If the control device does not soon correct the change, the operator may make suitable manual adjustment of the steam supply by actuation of the handle 97 of the hand switch 89. The hand switch 89 is also used when the 65 stock is changed and to adapt the system for use with different grades of paper.

In the event of a break or between runs when no sheet is passed over the rolls 10, the control device 63 becomes inoperative. It may be desired 70 to maintain the temperature of the rolls 10 substantially constant during this period so that the rolls will be ready for use when a sheet is again supplied thereto. For this purpose, the lever 158 is thrown to the opposite position, thereby disconnecting the hand switch 89 and connecting 75

the thermostat 90 to the motor-control unit 26. The thermostat 90 is adjusted to actuate the motor-control unit 26 so as to maintain the rolls 10 at a predetermined temperature.

When changing from the thermostat control to the hand switch, it is necessary to know the position of the motor-control unit 26 in order to make a corresponding setting of the hand switch. The indicating unit 120 is used for this purpose, since it operates in conjunction with the motor-control unit 26 and shows at all times the position thereof. It is obvious, however, that this unit may be omitted if such indication is not required in any particular instance.

It will be noted that the above device is adapted 15 to maintain the drying rolls at suitable temperatures to stabilize the moisture content of the finished sheet. In certain instances, the moisture readings were stabilized with a variation of 0.2%. The device also permits the rapid change-over 20 between different types of stock and eliminates waste due to improperly dried paper or due to breaks which are often caused by faulty drying. The adjustments are such that they may be readily adapted to any desired operating conditions, 25 and the controls are arranged on a panel suited to give a visible record of the operation of the system.

The position-indicating unit 120 shows at all times the position of the motor-control unit 26. 30 After a paper break or on change of orders, the operator sees instantly just where to position the handle 97 to pick up where the thermostat leaves off.

Under the close control herein provided, it is 35 possible to readjust the distribution of heat in the various rolls and to provide for balanced paper shrinkage across the mill, thereby reducing the breaks and improving the general quality of the paper. The ability to maintain a uniform and 40 correct drying roll temperature with proper distribution of the shrinkage across the whole mill permits increasing the speed, and therefore the tonnage, up to the limit of capacity of the mill.

The hand switch 89 may constitute a master 45 control for adjusting the system for different papers. The master control can position the valve in any one of twelve positions. The control switch 63 can position the valve in twenty-six 50 different positions. The relative control can be adjusted by varying the position of the slider 33 on the control lever 31. It is to be noted, therefore, that an extremely accurate control is effected.

The signal lights 85 may, for example, comprise red and green lights, and are adapted to 55 call the operator's attention to the fact that the sheet is too wet or too dry and that connection at the master control is required.

Although a preferred embodiment has been disclosed for purposes of illustration, it is evident that various changes and modifications may be made therein without departing from the scope of the invention, which is to be limited only in accordance with the following claims when interpreted in view of the prior art.

I claim:

1. A temperature-control device for paper mill drying rolls over which a sheet of paper is passed to be dried comprising, in combination, a source of heat supply to said rolls, a valve adapted to control said supply, a pair of reversible motor-control units adapted to jointly control the position of said valve, means responsive to variations in tension of the sheet due to variations in mois-

ture content thereof to actuate one of said units, a hand control, means responsive to the roll temperature, and means to actuate the second unit by either said hand-control or said temperature-responsive means.

2. A temperature-control device for paper mill drying rolls over which a sheet of paper is passed to be dried comprising, in combination, a source of heat supply to said rolls, a valve adapted to control said supply, a pair of reversible motor-control units adapted to jointly control the position of said valve, means responsive to variations in tension of the sheet due to variations in moisture content thereof to actuate one of said units, a hand control, means responsive to the roll temperature, means to actuate the second unit by either said hand-control or said temperature-responsive means, and an indicator unit adapted to indicate the position of said second unit so as to assist the operator in making manual adjustments by said hand control.

3. A device for controlling the temperature of drying rolls over which a sheet of paper is passed to be dried, which comprises means responsive to variations in tension of said sheet due to variations in moisture content thereof, a progressive successive multi-step reversible switch actuated by said means, a reversible motor-control unit actuated in accordance with the movement of said switch, a source of heat supply to said rolls, means actuated by said unit to control progressively said supply, means to limit the movement of said switch, a pair of signal circuits, and means operable when the switch remains in its respective limit positions for a given time to energize said circuits.

4. A device for controlling the temperature of drying rolls over which a sheet of paper is passed to be dried, which comprises means responsive to variations in tension of said sheet due to variations in moisture content thereof, a progressive reversible switch actuated by said means, a reversible motor-control unit actuated in accordance with the movement of said switch, a source of heat supply to said rolls, means actuated by said unit to control progressively said supply, means to limit the movement of said switch, a pair of signal circuits, thermostatic switches to control said circuits, a heating resistance associated with each of said thermostatic switches, and means to energize said heating resistances when said reversible switch is at the respective limits of its movement.

5. A device for controlling the temperature of drying rolls over which a sheet of paper is passed to be dried, which comprises a member adapted to press against the sheet for tensioning the same, a fluid cylinder, means responsive to movement of said member to control the supply of fluid to said cylinder, a piston actuated by said fluid, a progressive reversible control switch actuated by movement of said piston, a reversible motor control unit actuated in accordance with said control switch, a source of heat for said rolls, and means actuated by said motor-control unit to control said source.

6. A temperature control device for paper mill drying rolls over which a sheet of paper is passed to be dried comprising, in combination, a source of heat supply to said rolls, a valve adapted to control said supply, a pair of motor-control units, a variable ratio linkage connecting said units to said valve whereby the ratio of control effected by the respective units may be adjusted, means responsive to variations in moisture content of said

sheet to automatically actuate one of said units and a second control means adapted to actuate the other of said units.

7. A temperature-control device for paper mill drying rolls over which a sheet of paper is passed to be dried comprising, in combination, a source of heat supply to said rolls, a valve adapted to control said supply, a pair of reversible motor-control units adapted to jointly control the position of said valve, means responsive to variations in tension of the sheet due to variations in moisture content thereof to actuate one of said units, and a second control means adapted to actuate the other of said units.

8. A temperature-control device for paper mill drying rolls over which a sheet of paper is passed to be dried comprising, in combination, a source of heat supply to said rolls, a valve adapted to control said supply, a pair of reversible motor-control units adapted to jointly control the position of said valve, a progressive reversible switch adapted to control each of said units, means actuating one of said switches in accordance with the tension of said sheet, and manual means to actuate the other of said switches.

9. A temperature-control device for paper mill drying rolls over which a sheet of paper is passed to be dried comprising, in combination, a source of heat supply to said rolls, a valve adapted to control said supply, a pair of reversible motor-control units adapted to jointly control the position of said valve, a progressive reversible switch adapted to control each of said units, means actuating one of said switches in accordance with the tension of said sheet, and thermostatic means responsive to the roll temperature adapted to actuate the other of said switches.

10. A temperature control device for paper mill drying rolls over which a sheet of paper is passed to be dried, comprising, in combination, a source of heat supply to said rolls, a valve adapted to control said supply, a lever adapted to control said valve, a member adapted to press against said sheet for tensioning the same, integrating means responsive to the average position of said member over given time intervals, a belt actuated by said integrating means to control said lever between limits, and a motor-control unit adapted to control said lever within said limits, said motor-control unit also being actuated by said integrating device.

11. A temperature control device for paper mill drying rolls over which a sheet of paper is passed to be dried, comprising, in combination, a source of heat supply to said rolls, a valve adapted to control said supply, a lever adapted to control said valve, a member adapted to press against said sheet for tensioning the same, integrating means responsive to the average position of said member over given time intervals, a belt actuated by said integrating means to control said lever between limits, a motor-control unit adapted to control said lever within said limits, said motor-control unit also being actuated by said integrating device, and a master control adapted to change the range of control of said motor-control unit.

12. In a paper mill, in combination, a drying roll adapted to receive a sheet of paper to be dried, a source of steam supply therefor, a control valve for said steam supply, a pair of motor-control units adapted to independently control said valve, means automatically operating one of said units in response to variations in the moisture content of said sheet, and a second control means actuating the other of said units.

13. A device for controlling the temperature of drying rolls over which a sheet of paper is passed to be dried, which comprises a member adapted to press against the sheet for tensioning the same, 5 a fluid cylinder, means responsive to movement of said member to control the supply of fluid to said cylinder, a piston actuated by said fluid, a source of heat for said rolls, and means actuated in accordance with the position of said piston to control said source for varying the temperature of said rolls so as to compensate for variations in moisture of the incoming sheet.

14. A device for controlling the temperature of drying rolls over which a sheet of paper is

passed to be dried, which comprises a source of heat for said rolls, a progressive reversible control means for controlling said source, means responsive to variations in the moisture content of the sheet, a belt actuated by said last means, 5 said belt passing over said control means for actuating the same, means to limit the movement of said control means, said belt being adapted to slide thereover when the limit of movement of said control means has been reached or to permit 10 adjustment of said control means with respect to said belt.
